SACK HOLDER

John D. Diserens, La Russell, Mo.

Application September 5, 1950, Serial No. 183,216

3 Claims. (Cl. 248—97)

1

This invention relates to holders for sacks, bags and the like, the primary object being to provide a relatively inexpensive, light weight, easily operated device having arcuate arms swingably mounted for movement toward and away from each other and adapted to receive the bag to be held and to hold the mouth thereof in an open condition while the sack is being filled.

It is the most important object of the present invention to provide a sack holder that includes an upright standard having the aforesaid arms swingably secured thereto, and a base at the lower end thereof for supporting the standard and for mounting a swingable foot pedal that is operably joined with the arms to impart swinging movement thereto as the pedal is actuated.

Another important object of the present invention is the provision of a sack holder having means on the standard and connected with the structure interconnecting the swingable arms and the swingable foot pedal for yieldably holding the arms biased apart whereby to hold the open mouth of the sack in a stretched condition while the sack is being filled.

Other objects include the way in which a crank is pivotally secured to the standard and to the arms as well as the foot pedal by linkage so as to provide the proper leverage, and the way in which the arms are mounted on a plate-like head on the upper end of the standard for swinging movement thereon in a common horizontal plane.

Many more minor objects will be made clear or become apparent as the following specification progresses, reference being had to the accompanying drawing, wherein:

Figure 1 is a front perspective view of a sack holder made pursuant to my present invention.

Fig. 2 is a top plan view thereof showing the path of movement of the swingable sack holding arms; and

Fig. 3 is a fragmentary, cross-sectional view taken on irregular line III—III of Fig. 2.

The sack holder of this invention is well illustrated in the drawing and includes an elongated, preferably tubular, upright standard 10, mounted at the lowermost end thereof upon a U-shaped base broadly designated by the numeral 12.

Base 12 is provided with a pair of substantially parallel, elongated legs 14 and 16 and an elongated bight 18, all three parts of which are preferably L-shaped in cross-section as shown in Fig. 1 for strength and rigidity. The lower-

most end of the standard 10 is secured directly to the bight 18 intermediate the ends of the latter. Additional strength and sturdiness is attained through the medium of a pair of elongated braces 20 that are joined at the uppermost end thereof directly to standard 10 well above bight 18 of base 12 and at the lowermost ends of braces 20 to legs 14 and 16 intermediate the ends of the latter. Accordingly, the braces 20 converge as the standard 10 is approached and the lowermost ends of the braces 20 are spaced outwardly away from the lowermost end of the standard 10.

15 A head, broadly designated by the numeral 22, including a flat, horizontal plate 24 and a depending web 26 is secured directly to the standard 10 at the uppermost end thereof. Head 22 carries a pair of preferably identical arcuate arms 28 that are substantially semi-circular through the medium of a link 30 for each arm 28 respectively. The links 30 overlie the plate 24 and are pivotally secured thereto through the medium of spaced-apart, vertical bolts or the like 32.

20 25 One end of each arm 28 is secured directly to its corresponding link 30 on one side of the pivotal bolt 32 thereof. Each of the arms 28 is provided with a plurality of upwardly extending sharpened pins 34 spaced along the length thereof and on the outermost edges of arms 28.

30 35 The standard 10 is provided with a pair of spaced-apart, substantially parallel, laterally extending brackets 36 and 38 and leg 14 of base 12 is likewise provided with an elongated bracket 40, extending laterally beyond bight 18 in the same direction as brackets 36 and 38. The brackets 38 and 40 pivotally carry an elongated, horizontal shaft 42 having an elongated bar 44 rigidly secured to one end thereof and in turn provided with a foot pedal 46 at the outermost 40 free end of bar 44. It is noted that the bar 44 extends from the shaft 42 in the same direction as the leg 14 of base 12. That end of the shaft 42 opposite to the bar 44 has a short link 48 rigidly secured thereto.

45 50 The bracket 36 on standard 10 has a substantially T-shaped crank 50 pivotally secured thereto as at 52. An elongated reciprocable rod 54 has both ends thereof bifurcated, the uppermost end pivotally receiving one leg of the crank 50 as at 56 and the lowermost end of the rod 54 pivotally receiving the short link 48 as at 58. Another leg of the crank 50 pivotally receives a pair of identical links 60 as at 62 for each link 30 respectively. Each link 60 is pivotally secured to a correspond-

ing link 30 through the medium of a vertical bolt or the like 64 on that side of the pivotal bolt 32 opposite to the corresponding arm 28.

A vertical tube 66 is carried by the standard 10 adjacent the uppermost ends of the braces 20, which tube 66 loosely receives an elongated bolt 68 having a nut 70 threadably secured to the uppermost end thereof above tube 66. The lowermost end of the bolt 68 extending below tube 66 receives one end of a spring 72 that is in turn secured directly to the rod 54 adjacent the lowermost end of the latter.

When it is desired to place a sack or bag in a holding position with respect to the arms 28, the latter are caused to swing together against the bias of spring 72 as illustrated by dotted lines in Fig. 2 of the drawing. This springing movement of arms 28 toward each other is accomplished through the medium of downward movement on foot pedal 46 which swings bar 44 and the shaft 42 connected thereto as the latter rotates within the supporting brackets 38 and 40 therefor. Such rotative movement of the shaft 42 causes the short link 48 to swing toward the standard 10 and the rod 54 to reciprocate downwardly, all against the action of spring 72. As rod 54 so moves, crank 50 is caused to swing on the pivot 52 of bracket 36 which in turn retracts the links 60 in the manner illustrated by dotted lines in Fig. 2 and imparts swinging movement to the links 30 on pivot points 32. Such swinging movement of links 30 swings arms 28 to the dotted line position illustrated in Fig. 2. The operator can thereupon easily and quickly place the open end of the sack around the arms 28 in substantially circumscribing relationship thereto and at the same time secure the sack to the arms 28 by hooking the sack in sharpened pins 34 of arms 28. The operator thereupon releases the pressure upon foot pedal 46 and the spring 72 comes into operation to reverse the aforesaid movements and force the arms 28 outwardly toward the full line position illustrated in Figs. 1 and 2.

While the sack is being filled and as the same hangs below arms 28 resting upon any suitable supporting surface for base 12, the spring 72 will hold the arms 28 in a condition for maintaining the open end of the sack substantially circular. As soon as the sack is filled, the operator again presses downwardly upon the foot pedal 46 to move the arms 28 to a point where the sack may be released from the pins 34 and the sack may thereupon be tied and moved to a point of storage or loading from between the legs 14 and 16 of base 12.

It is seen that the standard 10 and all of its component parts are well supported by the base 12 against tipping movement in any direction and that neither the legs 14 and 16 nor the braces 20 will interfere with the sack being filled and depending from the arms 28. If desired, the base 12 may be rigidly secured to a supporting surface or to a mobile support of any suitable character. In any event, the entire sack holder is inexpensive to manufacture, easy to manipulate and capable of holding the sacks in a condition for filling without operator attention while the filling takes place. The sacks may be easily and quickly applied to the arms 28 and removed therefrom.

Many details of construction may be changed or varied within the spirit of this invention and therefore, it is desired to be limited only by the scope of the appended claims.

Having thus described the invention what is claimed as new and desired to be secured by Letters Patent is:

1. A sack holder comprising an elongated, upright standard having a base at the lowermost end thereof; a horizontal shaft rotatably carried by said base and said standard; a foot pedal secured to one end of said shaft; a head on the uppermost end of the standard; a pair of arcuate, sack-holding arms mounted at one end thereof on said head for swinging movement on spaced, vertical axes toward and away from each other; and structure operably interconnecting the shaft and said arms for swinging the latter on actuation of said foot pedal.

2. A sack holder comprising an elongated, upright standard having a base at the lowermost end thereof; a horizontal shaft rotatably carried by said base and said standard; a foot pedal secured to one end of said shaft; a link attached to the opposite end of the shaft; a reciprocable rod pivotally secured at one end thereof to said link; a head on the uppermost end of the standard; a pair of arcuate, sack-holding arms mounted at one end thereof on said head for swinging movement on spaced, vertical axes toward and away from each other; and structure operably interconnecting the rod and said arms for swinging the latter on actuation of said foot pedal.

3. A sack holder comprising an elongated, upright standard having a base at the lowermost end thereof; a horizontal shaft rotatably carried by said base and said standard; a foot pedal secured to one end of said shaft; a link attached to the opposite end of the shaft; a reciprocable rod pivotally secured at one end thereof to said link; a head on the uppermost end of the standard; a pair of arcuate, sack-holding arms mounted at one end thereof on said head for swinging movement on spaced, vertical axes toward and away from each other; and structure operably interconnecting the rod and said arms for swinging the latter on actuation of said foot pedal, said structure comprising a crank swingably secured to the standard and linkage pivotally joining said crank and each arm respectively, the crank being pivotally secured to the rod at the opposite end of the latter.

JOHN D. DISERENS.
